J. F. MacDONALD

TIRE INFLATING DEVICE

Filed July 30, 1924

Patented Feb. 16, 1926.

1,573,725

UNITED STATES PATENT OFFICE.

JOHN FRANKLIN MACDONALD, OF HILLSBORO, NEW BRUNSWICK, CANADA.

TIRE-INFLATING DEVICE.

Application filed July 30, 1924. Serial No. 729,168.

To all whom it may concern:

Be it known that I, JOHN FRANKLIN MACDONALD, a citizen of Canada, and a resident of Hillsboro, in the Province of New 5 Brunswick and the Dominion of Canada, have invented certain new and useful Improvements in Tire-Inflating Devices, of which the following is a specification.

This invention relates to a device for inflating tires, and is especially designed for inflating tires of the balloon type.

The object of the invention is to provide a device of this character and having the capacity mentioned and which is adapted to be operated from the engine of the automobile or motor vehicle with which it is associated.

A further object is to provide a device of this character which does not necessitate any modification of the engine structure, the inflater being associated with the spark plug opening of the cylinder head of the engine.

Other objects and advantages of the invention resides in the novel features of the construction, combination and arrangement of parts which will be hereinafter more fully described and particularly pointed out in the appended claims, reference being had to the accompanying drawings forming part of this specification, and in which:

Figure 1 is a view in vertical section, showing a portion of an engine having a device embodying the present invention associated therewith;

Figure 2 is a plan view of the device embodying the present invention;

Figure 3 is a fragmentary view thereof with parts broken away and shown in section for the sake of illustration;

Figure 4 is a view in horizontal section, on line 4-4 of Figure 1;

Figure 5 is a similar view on line 5-5 of Figure 1; and

Figure 6 is a view in horizontal section, on line 6-6 of Figure 3.

Referring to the drawings, the numeral 10 designates generally the cylinder of an automobile engine. As usual the engine includes at least four cylinders but only one is shown in the drawing for the sake of simplicity in illustration. A piston 11 is operatively mounted in the cylinder 10 in the usual manner. In the cylinder head 12 the usual internally threaded spark plug opening 13 is formed.

The present invention proposes the use of a specially constructed casing 15 having a reduced lower end 16 which is externally threaded and engaged with the threads of the spark plug opening 13. At its upper end the casing 15 is formed with flat wrench engaging surfaces 17. The casing 15 is designed to receive any conventional type of spark plug, and in the embodiment shown the spark plug is designated generally at 18, and comprises an insulator 19 of porcelain or the like which carries an electrode 20, the electrode 20 being cooperable with a second electrode 21 mounted on the casing 15, as shown in Figure 1. Of course the casing 15 is constructed of metal, and is grounded on the engine in the usual manner. The insulator 19 is formed with a shoulder 22 which engages a gasket 23 interposed between the shoulder 22 and a seat 24 provided in the casing 15. Of course the casing 15 is formed with an opening to receive the spark plug 18, the said opening being designated generally at 25. The spark plug 18 is held in position in the casing 15 by means of a retaining nut 26 threadedly engaged with the casing 15 and having its inner end engaging a gasket 27, the latter being engaged with a shoulder 28 formed on the insulator 19.

The casing 15 is also provided with a passage 30 which communicates with the working chamber or working space of the engine cylinder and which leads up to a cylindrical valve chamber 31 provided in the upper end of the casing 15, and in which a pressure operated piston valve 32 is slidably fitted. Communication between the passage 30 and the valve chamber 31 is controlled by a manually operable shut-off valve 33 which preferably takes the form of a tapered plug snugly fitted in a transverse opening 34 provided in the casing 15, and intersecting the passage 30. The plug 33 is held in frictional engagement with the wall of the opening 34 by means of washer 35 engaged with a shoulder 36 of the casing 15 and connected with the small end of the plug valve 33 by means of a screw 37, the screw 37 extending loosely through an opening in the washer 35. A pin 38 is formed on the washer 35 and is snugly fitted in an opening provided therefor in the valve 33 to constrain the washer to rotate with the valve. A slight clearance is provided between the small end of the valve and the

washer 35 in order that the necessary take-up may be had to compensate for wear. At its large end the valve 33 is formed with a squared operating head 39 adapted to be engaged by a wrench when the valve 33 is to be turned. The valve 33 is held in open or closed position by virtue of its frictional engagement with the wall of the opening 34.

A plurality of inlet ports 40 are provided 10 in the casing 15 and extend from the atmosphere into the chamber 31. An outlet port 41 is also formed in the casing 15 and extends into the valve chamber 31. Preferably the ports 40 and 41 communicate 15 with the chamber at the same horizontal level but these ports are spaced from each other angularly. The ports 40 lead out through the side of the casing but the port 41 leads up through the top of the casing 20 and is adapted for connection with an air line leading to the tires to be inflated.

The piston valve 32 includes a head 42 and a skirt 43. In assembling the piston valve with the casing, the valve is introduced through an opening 44 provided in the top of the casing and leading directly into the chamber 31. After the piston valve has been fitted in the chamber 31, the opening 44 is closed by a plug 45 having a vent 46 therein. In order to constrain the valve 32 to rectilinear sliding movement in the chamber 31, a pin 47 is fixed to the skirt of the piston and is slidably fitted in a longitudinal groove 48 formed in the wall of the 35 valve chamber 31. The skirt of the piston is provided with a plurality of ports 49 designed to be registered with the inlet ports 40 of the casing 15 when the valve 32 is in its lowermost position in the chamber 31, the 40 ports 49 being located immediately below the head 42 of the piston valve. A single port 50 is also provided in the skirt of the piston adjacent its lower end and is designed to register with the port 41 of the casing 45 when the piston valve is in its uppermost position in the chamber 31, as shown in Figure 3.

With this arrangement when the inflater is not in use, the valve 33 is closed and the 50 engine operates in the usual manner. The piston valve 32 is inactive when the valve 33 is closed.

When it is desired to use the inflater, the 55 spark plug 18 is disconnected from the ignition system of the engine and the cylinder with which the inflater is associated is idle in the operation of the engine but active to the end of inflating the tires as will presently appear. The valve 33 having been 60 opened and the piston 11 being reciprocated in the cylinder 10, air will be drawn into the cylinder on the down stroke of the piston, since the cylinder communicates with the atmosphere through the passage 30, the port 65 of the valve 33, and the ports 49 and 40 of

the casing, the ports 49 and 40 being in registry as the valve 32 has been drawn down to the position shown in Figure 1 by the action of the suction induced by the downward movement of the piston 11. On the up-stroke of the piston the pressure operated valve 32 is forced up to the position shown in Figure 3 in which position of the valve 32 the inlet ports 40 are closed by the imperforate portions of the skirt 43 of the piston 70 valve 32. The outlet port 41 is however in registry with the port 50 of the skirt of the piston and thus the air expelled from the cylinder of the engine passes out through the port 41 and through the air line connected 75 thereto to the tires.

The present invention is especially designed and adapted for use in inflating tires of the balloon type.

I claim:

1. In a tire inflater of the character described, in combination with an engine having a cylinder and a piston operating therein, a casing mounted on the cylinder, said casing having a passage communicating with the interior of the cylinder, means for controlling communication of said passage with said cylinder, said casing having a valve chamber communicating with the cylinder when said passage is open, said casing having an intake port leading from the atmosphere into the valve chamber, said casing also having an outlet port leading from said valve chamber, a pressure operated piston valve fitted in the valve chamber and having ports therein alternately cooperatable with the intake and outlet ports of the casing under the influence of the piston of the cylinder, cooperating means between the piston valve and the casing for constraining the piston valve to rectilinear movement, and a vented plug threaded into the casing and affording a stop for one end of said piston valve.

2. In a tire inflater of the character described, in combination with an engine having a cylinder and a piston operating therein, a casing mounted on the cylinder, said casing having a passage communicating with the interior of the cylinder and also having a valve chamber communicating with said passage, a manually operable valve controlling communication between the passage and the valve chamber, said casing having an inlet port leading from the atmosphere into the valve chamber and also having an outlet port leading from the valve chamber, and a pressure operated piston valve operatively fitted in the valve chamber and having ports therein alternately and automatically cooperable with the intake and outlet ports of the casing under the influence of the piston of the cylinder.

JOHN FRANKLIN MacDONALD.
